JEAN PROSPER MATHERET, OF PARIS, FRANCE.

PROCESS OF MANUFACTURING DENTAL PLATES.

SPECIFICATION forming part of Letters Patent No. 784,060, dated March 7, 1905.

Application filed August 16, 1904. Serial No. 220,934.

To all whom it may concern:

Be it known that I, JEAN PROSPER MATHERET, a citizen of the Republic of France, residing at 8 Rue de Valois, Paris, France, have invented new and useful Improvements in Processes for the Manufacture of Dental Plates, of which the following is a specification.

This invention relates to an improved process for the manufacture of dental plates.

10 In the accompanying drawings, Figure 1 is a perspective view of the plaster cast; Fig. 2, a perspective view of the first matrix; Fig. 3, a perspective view of the second matrix. Fig. 4 is a sectional view of the first matrix and 15 one of the plungers with the gold foil between them. Fig. 5 is a view of the finished plate.

A first impression of the jaw is taken with wax. On this wax a plaster cast, Fig. 1, is 20 molded, and by means of the latter two matrices are produced—a first matrix of cast iron or steel, Fig. 2, the inequalities of which are made to disappear by chasing; a second controlling-matrix, Fig. 3, obtained by the galvanoplastic process. The latter process furnishes a copper sheet which reproduces exactly the plaster cast and which is rendered 25 solid by means of a zinc filling. By means of these two matrices employed consecutively 30 the dental plate is obtained. To this purpose the gold foil A is swaged at first in the matrix B, of cast iron or steel, Fig. 4, by means of three consecutive plungers C of increasing 35 hardness made with the aid of the same matrix. A first plunger of lead is obtained by swaging a mass of lead in the cast-iron matrix, and the gold plate is swaged in the same matrix with the aid of said first plunger. A

copper sheet is then placed into this matrix and molded on the first lead plunger, there 40 being thus obtained a copper-covered lead plunger, with which the gold plate is swaged a second time in the matrix of cast-iron. Finally, a third plunger is made entirely of copper by means of swaging in the matrix of cast 45 iron or steel a mass of copper heated to white heat. The gold plate is swaged by means of the third plunger at first in the first matrix and then in the controlling-matrix obtained by the galvanoplastic method. A dental plate 50 D, Fig. 5, is thus obtained which is an exact reproduction of the plaster cast molded with the wax impression taken on the jaw.

What I claim is—

The improved process for the manufacture 55 of dental plates, which consists in first making by means of a plaster mold made from the wax impression taken from the mouth, two matrices, one by casting cast iron or steel around the plaster, and the other by means of 60 electro-deposition, the electro-deposited matrix being strengthened externally by means of a filling or backing of zinc or other material; then striking a gold plate successively in the two matrices by means of consecutive dies 65 of increasing hardness produced by casting or striking masses of lead and copper or other metals in the cast iron or steel matrix, substantially as described.

In testimony whereof I have signed my name 70 to this specification in the presence of two subscribing witnesses.

JEAN PROSPER MATHERET.
